UNITED STATES PATENT OFFICE.

ELI EPSTEIN, OF BOSTON, MASSACHUSETTS.

CYLINDER-LOCK.

1,135,998.

Specification of Letters Patent. Patented Apr. 20, 1915.

Application filed November 5, 1914. Serial No. 870,337.

To all whom it may concern:

Be it known that I, ELI EPSTEIN, a subject of the Czar of Russia, residing at Boston, county of Suffolk, State of Massachusetts, have invented an Improvement in Cylinder-Locks, of which the following description, in connection with the accompanying drawing, is a specification, like characters on the drawing representing like parts.

10 This invention relates to cylinder locks and has for its object to provide a novel construction by which the cylinder is locked into the barrel in such a way that it cannot be removed after the parts are once assembled without destroying the lock. In the cylinder lock as usually made the cylinder can be removed from the barrel comparatively easily after the multi-part tumbler pins have been lined up, and an expert locksmith can 15 readily line up the tumbler pins even though he has not a key by giving the lock jarring blows. This fact opens the way for unauthorized persons to secure improperly a duplicate key of the lock, for the making of the 20 duplicate key involves simply removing the cylinder from the lock and then filing a key to fit the tumblers of the lock, after which the cylinder can be placed back in the lock again. My invention obviates the possibility 25 of this being done by providing a construction which prevents the cylinder from being removed from the barrel after the parts have once been assembled. With my 30 improvements it is impossible for any person to make a duplicate key except from the original key. The construction also has the 35 advantage that it renders the lock non-pickable.

In order to give an understanding of my 40 invention I have illustrated in the drawings a selected embodiment thereof which will now be described, after which the novel features will be pointed out in the appended claim.

45 Figure 1 is a vertical sectional view of a duplex cylinder lock on substantially the line $x-x$, Fig. 2; Fig. 2 is a sectional view on the line $y-y$, Fig. 1; Fig. 3 is a perspective view of the cylinder removed; Fig. 50 4 is a perspective view of the locking ring.

The lock herein shown comprises the usual casing or barrel 1 having a bore to receive the cylinder 2 which is provided with the usual key slot 3.

55 4 represents the usual multi-part tumbler pins which are received in apertures formed

in the barrel and cylinder, respectively, said pins being acted upon by springs 6.

The parts thus far described are such as are commonly found in cylinder locks and 60 form no part of my present invention.

In order to lock the cylinder in the barrel so as to prevent the possibility of its being removed under any circumstances, I have herein provided the cylinder with a groove 65 7 and have provided the bore in the barrel with a mating groove 8, and have also provided a split locking ring 9 which is adapted to be received in said grooves thereby to lock the cylinder in the barrel. The groove 7 is 70 deep enough and the locking ring 9 is a spring ring so that in assembling the parts the ring 9 can be placed into the groove 7 and then compressed to permit the cylinder to be inserted into the barrel. When the cylinder 75 is in place the groove 7 is opposite the groove 8 and the resiliency of the ring 9 will cause it to spring out into the groove 8 so that the ring will be normally situated partly in the groove 8 and partly in the 80 groove 7. By this means the cylinder is positively locked in the barrel and cannot be removed therefrom. This locking means is independent from the tumbler pins 4 so that even when the tumbler pins are lined 85 up the cylinder is still locked in the barrel. The gap or opening 10 in the split ring 9 is of sufficient width to receive the key 11, and in assembling the parts it is essential that the ring 9 should be so positioned that the space 90 10 will come in alignment with the key slot. This is necessary in order to permit the key to be inserted into the slot in order that the locking ring 9 may not form an obstruction to the entrance of the key into the cylinder 95 3. When the key is inserted and the cylinder is turned by the key, the engagement of the back of the key with the ends of the ring 9 will turn the ring with the cylinder, and as the key cannot be withdrawn except when 100 it is in the position shown in Fig. 2, it will be obvious that whenever the key is removed from the lock the locking ring 9 will always be left with the gap or space 10 therein in alignment with the key slot.

105 With my invention it is impossible for any person to remove the cylinder from the lock for the purpose of making a key to fit the cylinder or for any other purpose. The lock will thus be of use only so long as the original keys are available and when these have become lost or broken a new lock will be 110

required. The presence of the ring 9 also makes it impossible for a person to pick the lock by inserting a thin-bladed instrument between the cylinder and the bore in the barrel thereby to hold the tumbler pins in their unlocked position as they are successively lined up by means of a false key.

I claim:

In a cylinder lock, the combination with a barrel having a bore provided with an annular groove intermediate of its ends, of a cylinder operating in said bore and provided with a key slot and a peripheral groove in alignment with the groove in said

bore, tumbler pins carried by the cylinder 15 and barrel, and a split locking ring received in said grooves and locking the cylinder in position, the space or gap between the ends of the split ring being in alignment with the key slot of the cylinder. 20

In testimony whereof, I have signed my name to this specification, in the presence of two subscribing witnesses.

ELI EPSTEIN.

Witnesses:

LOUIS C. SMITH,
THOMAS J. DRUMMOND.
